His Attorneys.

UNITED STATES PATENT OFFICE.

ORVILLE O. SHELINE, OF CHICAGO, ILLINOIS, ASSIGNOR TO BURNITOL MANUFACTURING COMPANY, OF EVERETT, MASSACHUSETTS, A CORPORATION OF MAINE.

RECEPTACLE.

1,274,613.

Specification of Letters Patent.

Patented Aug. 6, 1918.

Application filed December 8, 1917. Serial No. 206,277.

To all whom it may concern:

Be it known that I, ORVILLE O. SHELINE, a citizen of the United States, and resident of Chicago, in the county of Cook and State 5 of Illinois, have invented new and useful Improvements in Receptacles, of which the following is a specification.

This invention relates to receptacles and more particularly to paper receptacles de- 10 signed for use as sputum flasks.

The principal object of the invention is to produce a flask which can be cheaply and readily constructed, which will rigidly hold together after being assembled, which is 15 preferably formed from a single sheet of material, which has improved means for locking the end portions to the side portions after the sheet of material has been folded into the desired form of receptacle, 20 which preferably has bellows ends, and which has an exceedingly tight and close fitting cover, the cover preferably being arranged to cooperate with the locking means to hold it in closed position.

25 Other objects of the invention will be apparent from the following description taken in connection with the accompanying drawings, in which,—

Figure 1 is a plan view of the blank 30 from which the receptacle is constructed;

Fig. 2 is a similar view showing the blank partially folded to form the receptacle;

Fig. 3 is a similar view showing an advanced stage of the folding operation;

35 Fig. 4 is a similar view, parts being broken away, showing a still further stage of the folding operation;

Fig. 5 is a similar view showing a still further stage;

40 Fig. 6 is a similar view showing a still further stage.

Fig. 7 is a similar view showing the receptacle completely assembled, with the ends extending outwardly, and having its cover 45 raised;

Fig. 8 is a view identical with Fig. 7, except that the ends of the receptacle are folded inwardly into normal position, the receptacle being partly compressed together;

50 Fig. 9 is a front elevation of the receptacle in closed condition;

Fig. 10 is a vertical central section of the receptacle in completely assembled but opened position; and

55 Fig. 11 is a vertical central section, taken

on line 11—11 of Fig. 9, showing the receptacle in closed condition.

While the structure of my improved receptacle may take any one of many forms within the scope of the present invention 60 as defined by the appended claims, it is preferably substantially that illustrated in the drawings. The particular structure chosen for the purpose of illustration is formed from a single sheet of material stamped or 65 otherwise cut in the shape shown in Fig. 1. The lines inside of the outline of this blank indicate the axes along which the various parts of the blank are folded to produce the receptacle. These parts comprise a back 70 portion 1, a front portion 2, lateral portions 3 and 4 adapted to be folded along the back portion, portions 5 and 6 which form the bellows ends of the receptacle when assembled, parts 7 and 8 which are intended to be 75 folded along the front portion 2, portions 9 and 10 forming integral extensions of portions 6 and 7 and locking certain parts together as hereinafter described, portions 11 and 12 which are preferably formed as an 80 integral extension of one of the lateral portions 3, and the cover comprising portions 13, 14, 15 and 16. After the blank shown in Fig. 1 has been stamped out, or at the same time as the blank is being cut out, it 85 is preferably scored along the lines shown in Fig. 1 so that it may be folded along these lines.

After the blank has been stamped and scored it is preferably folded together in 90 substantially the following manner: The left-hand portion 3 is folded inwardly along the inside of back portion 1, as shown in Fig. 2, the left-hand portion 4 is then folded outwardly along the left-hand portion 3, the 95 portion 4 being shown in a position slightly in advance of its final position in Fig. 3, and the right-hand portion 3 is then folded over the left-hand portions 3 and 4, the right-hand portion 3 being moved partly into position in Fig. 3. When the parts 3 and 4 have been placed in their final position they lie against each other and against the back portion 1, each portion being parallel to the back portion 1, as shown for example in the 100 sectional views in Figs. 10 and 11. After the parts 3 and 4 have been folded into this position the extensions 11—12 on the left-hand member 3 are folded downwardly over the portions 3 and 4, as shown in Fig. 4. 110

The flap 12 at one side of the extension 11 is then folded under the right-hand members 3 and 4, as shown in Fig. 5, it being understood that the parts are sufficiently flexible 5 to allow them to be sprung somewhat. After the flap 12 has been placed in this position the parts 3 and 4 are held together and the parts are also held against the back 1.

After the back portion of the receptacle 10 has been folded together in the above described manner, the front portion is assembled in the following manner, although it is possible to assemble the front portion before the rear portion. The portion 8 is folded 15 inwardly along the inside of the front 2 and the portion 7 is folded outwardly along the portion 8 as shown in Fig. 6. These three parts, namely, parts 7, 8 and 2, are then compressed together so that they lie in part- 20 allelism, and the front 2 is flexed so that its upper edge is substantially in alinement with the upper edge of section 6. The extension 9—10 on parts 6 and 7 may then be folded outwardly along the line between 25 parts 9 and 10, and parts 6 and 7 over the part 8 and the front 2. Then by allowing the front 2 to flex outwardly into normal position the extension 9—10 is bent about the line between the parts 9 and 10, as shown 30 in Fig. 7, on which position the extension 9—10 cannot be folded upwardly but is locked in position. The manner of locking parts 9 and 10 over parts 7, 8 and 2 is the same for both sides, so that the above de- 35 scription will explain the manner of securing both sides together. The receptacle now is in the condition shown in Fig. 7. The ends 5 and 6 are then folded inwardly instead of outwardly as shown in Fig. 8, and the recep- 40 tacle is in completely assembled condition.

In order to close the receptacle the front and back are pressed together and the cover is folded forwardly over the top of the receptacle, which is comparatively narrow as 45 shown in Fig. 11. The base 13 of the cover is positioned over the mouth of the receptacle as shown in Fig. 11 and the portions 14, 15 and 16 function to hold the base of the cover in this position, the portion 14 50 folding downwardly along the front 2 and the portion 15 folding upwardly into the pockets or recesses under the portions 10 of the locking extensions 9—10. The tab 16, which is struck-up from the portion 15 of 55 the cover, extends downwardly as shown in Fig. 9 and affords means whereby the portion 15 may be conveniently pulled out from under the portions 10 to uncover the receptacle. As shown in Figs. 10 and 11, the ends 60 of the receptacle comprise parts 5, 6, and 17, the parts 5 and 6 folding inwardly so as not to be visible when the receptacle is closed. The end portion 17 is preferably scored 65 along its vertical center line, as is also the bottom 18, so that the receptacle when in

closed position may be tightly pressed together so as to occupy a very small space. However, it is to be understood that the scoring in the ends 17 and the bottom 18 may be omitted and that the ends 17 and 70 bottom 18 may be as narrow as desired, it being possible to make them of negligible width.

A receptacle having the novel characteristics recited in the appended claims is ex- 75 ceedingly easy and inexpensive to construct, it being formed completely of a single piece of paper or other suitable material, the parts are tightly locked together, the receptacle can be extended at the top by virtue of the 80 bellows ends 5 and 6, and the cover can be tightly and quickly secured over the mouth of the receptacle so as to render the device practically non-spillable.

I claim:

1. A receptacle one side of which comprises a central portion and two lateral portions folded inwardly along the central portion, and a flap on one of said lateral portions folded over one of the other portions 90 and then folded under one of said portions so as to hold the portions together.

2. A receptacle comprising a wall portion, second and third wall portions connected to two sides of said first portion, the second 95 and third portions being folded along said first portion, and a flap on said second portion folding over and then under said third portion so as to hold the three portions together.

3. A receptacle comprising a central wall portion, two lateral wall portions connected to opposite sides of the central portion and folded along the central portion, and a flap on one of the lateral portions folded over and then under the other lateral portion so as to hold the portions together. 105

4. A receptacle comprising a central wall portion, two lateral wall portions, at least 110 one of said lateral wall portions being folded inwardly and then outwardly along the central wall portion and the other lateral portion being folded inwardly along the central portion, and a flap on the latter portion folding over and then under the other lateral portion so as to hold the portions together. 115

5. A receptacle comprising a central portion and two lateral portions connected to opposite sides of the central portion, each 120 of the lateral portions being folded inwardly and then outwardly along the central portion, and a flap on one of said lateral portions folded over and then under the other lateral portion so as to hold the portions together. 125

6. A receptacle comprising a central portion and two lateral portions connected to opposite sides of the central portion, each 130 of the lateral portions being folded in-

wardly and then outwardly along the central portion, and a flap on one lateral portion folded over and then under the other lateral portion, the axis of the second fold 5 of the flap being substantially collinear with the axis of the second fold of the other lateral portion.

7. A receptacle comprising a central portion and two lateral portions connected to 10 opposite sides of the central portion, each of the lateral portions being folded inwardly and then outwardly along the central portion, the axes about which each lateral portion is folded being oblique to each other, 15 and a flap on one lateral portion folded over and then under the other lateral portion, the axis of the second fold of the flap being substantially collinear with the axis of the second fold of the other lateral portion.

20 8. A receptacle comprising a central portion, two triangular lateral portions each folded along the central portion about one of its sides, a flap on the other side of one of the lateral portions folded over and then 25 under the other lateral portion, the second fold of the flap being over and around the hypotenuse of the other lateral portion.

9. A receptacle comprising a substantially 30 rectangular central portion, two substantially rectangular lateral portions connected to opposite sides of the central portion, the lateral portions being folded inwardly along the opposite sides of the central portion and then outwardly about axes oblique to the 35 opposite sides of the central portion respectively, and a flap on one of the portions folded over the lateral portions and around the oblique axis of one of the lateral portions so as to hold the portions together.

40 10. A receptacle comprising two adjacent wall portions folded together, and an extension on one of the portions folded over the first fold about an axis transverse of the first fold to hold the two portions together.

45 11. A receptacle comprising two integral walls meeting at a corner, one wall having a fold extending along the other wall, and an extension on one wall extending on both sides of said corner folded over said fold to hold the fold against the other wall.

50 12. A receptacle comprising two integral walls meeting at a corner, one wall being folded inwardly and then outwardly along the other wall and then being bent transversely of the other wall, and an extension 55 on the one wall disposed in part on each side of said bend, the extension being folded

over said corner with a part lying along each wall.

13. A receptacle comprising two walls 60 meeting at an angle along a corner, a fold integrally connecting the two walls together at the corner, the fold lying along one wall, and an extension disposed in part along an edge of the fold and in part along an edge 65 of the other wall, the extension being folded over the corner with a part lying along each wall to hold the fold against the other wall.

14. A receptacle comprising a side wall and an end wall meeting at an angle to form 70 a corner, a gusset connecting along opposite sides with the two walls at said corner and being folded along the side wall, a tab extending along the contiguous edges of said gusset and end wall and being adapted to 75 fold over the side wall when the end and side walls are moved approximately into the same plane, the tab then being adapted to bend around said corner when the sides are again moved into angular relationship so 80 that it can not be unfolded, thereby to lock the side and end walls together with the gusset folded along the side wall so long as the walls are maintained in angular relationship.

85 15. A receptacle comprising two opposite walls, a cover pivotally mounted on one wall and extending over and along the other wall when in closed position, one or more recesses 90 in said other wall opening downwardly on the outer side, and an extension on said cover adapted to be turned under and inserted into said recesses.

16. A receptacle comprising two opposite walls, one of said walls having one or more 95 downwardly directed pockets on its outer side, and the other wall having a cover extending over the receptacle and downwardly along said one wall, and an extension on the cover folding inwardly and upwardly into 100 said pockets.

17. A receptacle comprising two opposite walls, one of said walls having one or more downwardly directed pockets on its outer side, and the other wall having a cover extending over the receptacle and downwardly along said one wall, an extension on the cover folding inwardly and upwardly into 105 said pockets, and a struck up tongue on said cover extending outwardly from its forward side.

Signed by me at Chicago, Illinois, this 13th day of August, 1917.

ORVILLE O. SHELINE.
